UNITED STATES PATENT OFFICE.

SAMUEL H. HODGES, OF PARISH OF STREET, COUNTY OF SOMERSET, ENGLAND, ASSIGNOR OF ONE-HALF TO GEORGE E. BARNARD, OF LYNN, MASSACHUSETTS.

PAPER-MAKING MACHINE.

SPECIFICATION forming part of Letters Patent No. 335,030, dated January 26, 1886.

Application filed October 26, 1885. Serial No. 180,947. (No model.)

To all whom it may concern:

Be it known that I, SAMUEL HORATIO HODGES, residing in the Parish of Street, county of Somerset, England, have invented an Improvement in Paper-Making Machines, of which the following description, in connection with the accompanying drawings, is a specification, like letters on the drawings representing like parts.

10 This invention has for its object to improve paper-making machines of the cylinder class employed in the production of paper-board or so-called "leather-board," in order that the direction of the travel of the pulp may be changed from time to time to effect the distribution of the floating fiber of the pulp in different directions upon the forming cylinder, the web taken up by the said forming-cylinder being so placed, one layer or portion with relation 15 to another, on the usual press-roll as to leave the fibers of the different layers crossing each other.

In machines now commonly employed in the manufacture of paper-board, or so-called "leather-board," the fiber is deposited upon a wire-covered forming-cylinder, which is rotated in the presence of the pulp in a vat, and the fiber is kept from settling in the vat by means of an agitator; but the fiber so deposited 20 is laid substantially in the direction of rotation of the cylinder, and as a result the layers of paper taken from the forming-cylinder by the usual belt and couching-roller and applied to the press-roll has its fiber all substantially 25 in the same direction, and the paper produced is left very strong in one and very weak in the other direction.

It is a great desideratum to produce paper-board or leather-board equally strong in all 30 directions; and to do this I have provided means for generating in the pulp a current in one and then in another direction, whereby the fiber laid upon the forming-cylinder will for a time be diverted in one direction and 35 then in another direction, so that the pulp-web when deposited in layers one upon the other on the press-roll may present its fibers in different directions, or so as to cross each other.

50 My invention consists, essentially, in the combination, with a pulp-vat and a rotating forming-cylinder placed therein, of means for forc-

ing the said pulp into the vat alternately or at will from opposite sides, thus changing at predetermined intervals the direction of flow of 55 the pulp in the vat next the forming-cylinder, thereby enabling the fiber in the pulp and being taken up by the forming-cylinder to be laid thereon at different angles, substantially as will be described.

Figure 1 in cross-section represents a pulp-vat and forming-cylinder with my improvement added to the pulp-vat, and Fig. 2, a left-hand elevation of Fig. 1.

The pulp-vat A and forming-cylinder there- 60 in are and may be of usual construction or such as commonly employed in the manufacture of paper-board or so-called "leather-board."

In the formation of the board described, the pulp deposited upon the forming-cylinder is 65 taken therefrom by means of an endless belt passed over couching-rollers, the pulp-web de- 70 posited upon the endless belt being delivered therefrom usually upon a press-roller, about which it is accumulated until it is of sufficient 75 thickness for the board to be made, when the accumulated material in numerous layers is cut through longitudinally with relation to the roll, and the material is removed as a sheet or slab having a length equal to the circumfer- 80 ence of the roller. In case the fiber in the pulp- 85 vat all runs in substantially the same direction, the material wound upon the roller is strong in one direction—namely, that of the length of the fiber—but weak in the reverse direction.

In accordance with my invention, I have provided a rotary or other usual forcing-pump, C, which, by a pipe, D, is in communication with the pulp-vat A. The pump has an outlet, C', and a valve-chamber, C², having two outlets, 23, and within the valve-chamber is a valve, a, connected with a rod, a', joined to a link, a², which is reciprocated to move the valve by means of an eccentric, a³, on the small shaft a⁴, having its bearings in uprights a⁵, the said shaft having attached to it a pulley, b, driven by a suitable belt, b², set in motion by a counter or other usual shaft, the said shaft a⁴ being rotated slowly, so as to cause 90 the valve a to close first one and then the other of the outlets 23 for a length of time corresponding substantially with that required for 95 each complete rotation of the forming-cylin- 100

der in the pulp-vat. The outlet 2 has connected with it a pipe, e , which is led across the pulp-vat and bent down, so that its end enters the pulp-vat near the level of the pulp. 5 The outlet 3 has connected with it a short pipe, e' , which leads into the pulp-vat at its other side, as shown in the drawings, Fig. 1.

In practice the forming-cylinder B, having a reticulated surface, will be rotated in any usual 10 manner, and the pulp-stock used will be of any usual material and consistency.

The pump herein shown as one of the rotary class may be of any usual construction, and as herein shown it will be driven by a belt on 15 the pulley e^a , attached to its shaft. While the forming-cylinder is being rotated to take up the fiber in the pulp, the pump will be operated so as to draw a portion of the pulp from the pulp-vat through the pipe D and discharge 20 the pulp into the valve-chamber C^a , from which it will be forced by the pump through the pipes $e e'$, one or the other, that depending upon which one of the outlets 2 3 is uncovered.

In the drawings, the outlet 3 is covered, and 25 the pulp is supposed to be passing through the pipe e into the right-hand end of the pulp-vat, which operation establishes a current in the pulp that tends to effect the loading of the fiber upon the forming-cylinder in the direction of the dashes f . The outlet 2 will be left open and the pulp will be discharged in the pulp-vat through the pipe e , preferably for a 30 length of time sufficient to enable the forming-cylinder to rotate one or more times, and then 35 the valve a will be moved to cover the outlet 2 and uncover the outlet 3, when the pulp in the valve-chamber C^a will thereafter pass into the pulp-vat through the pipe e' , changing the current of the pulp in the vat, 40 so as to effect the loading of the fibers on the forming-chamber substantially in the direction of the dashes f' , and the current will be continued in this direction until the forming-cylinder has made one or more rotations. As 45 a result of the change of direction of the current in the pulp-vat, the fibers are inclined first in one direction and then in the opposite direction, so that the fibers in the pulp as deposited upon the forming-cylinder are for one 50 or more rotations of the cylinder inclined in one direction, and then for one or more rotations of the cylinder in an opposite direction, and the pulp-web taken from the forming-cylinder by the endless felt will have its fibers 55 laid at intervals in opposite directions, or nearly so, and as the pulp on the endless felt is applied to it, accumulating upon the press-roller, so that the fibers in different portions thereof are made to cross each other at an angle, 60 which will add very materially to the strength of the paper or leather board which will be produced.

I do not desire or intend to limit my invention to the employment of the pump of the 65 particular kind herein shown, as, instead thereof, I may employ any well-known or equivalent apparatus by which to keep the

thin or reduced pulp in motion in the vat in a direction parallel, or substantially so, to the axis of rotation of the forming-cylinder; nor 70 do I desire to limit my invention to the exact location of the pump with relation to the pulp-vat, nor to the exact construction of the valve, for, instead of the valve shown, I may employ any other usual valve capable of opening and 75 closing one port or outlet after the other in the desired time and order.

I have herein shown the pulp-vat as provided with but one forming-cylinder, and I have shown two pipes, $e e'$, to operate alternately in changing the direction of the current of the pulp at that side of the forming-cylinder upon which the pulp is deposited. 8c

I desire it to be understood that as a modification of my invention I might employ two 85 forming-cylinders, and that the pipe e might operate to establish the current at the forming side of one cylinder in one direction while the pipe e' would be made to establish a current at the forming side of the second cylinder, 90 but in an opposite direction; but in such case the valve would be omitted.

In the modification referred to the fibers taken up by one cylinder would be inclined in a direction opposite that of the fiber taken up by the other cylinder, and as the material upon each cylinder is thereafter applied to the endless felt, one layer after the other, it will be seen that the fibers in the successive layers would cross each other, substantially as herein-before provided for, thus strengthening the 100 completed web.

I claim—

1. In a paper-making machine, a pulp-vat and a forming-cylinder therein, combined 105 with a pump and a pipe to connect it with the pulp-vat, the pump operating to force the pulp into the pulp-vat in a direction parallel, or nearly so, to the axis of rotation of the forming-cylinder, to thereby establish a cross-current in the pulp-vat, substantially as described.

2. In a paper-making machine, a pulp-vat and one or more forming-cylinders therein, combined with a series of pipes and with a 115 pump to force the pulp through one and then the other of the said pipes, in order to change at intervals the direction of the flow of the pulp in and through the said pulp-vat, for the 120 purposes set forth.

3. The pulp-vat, a pipe, D, connected therewith, a pump, a valve-chamber and valve 125 therein, combined with a forming-cylinder located within the pulp-vat, and with pipes $e e'$, through which the pulp is forced into the pulp-vat to change the direction of the current therein, substantially as described.

In testimony whereof I have signed my name to this specification in the presence of two subscribing witnesses.

SAMUEL H. HODGES.
